CLAIM

The ornamental design for a handbag, as shown and described.

DESCRIPTION

FIG. 1 is a front perspective view of the handbag showing our new design;

FIG. 2 is a top view of the handbag and the shoulder strap has been omitted to better show the top of the handbag;

FIG. 3 is a bottom view of the handbag;

FIG. 4 is a front elevational view of the handbag;

FIG. 5 is a rear elevational view of the handbag;

FIG. 6 is an elevational view of the left side of the handbag; and,

FIG. 7 is an elevational of the right side of the handbag.

The dash lines are part of the design and show stitching.
